UNITED STATES PATENT OFFICE.

ROBERT FRIEND, OF LOWELL, MASSACHUSETTS.

APPARATUS FOR SEALING WAXED PAPERS.

1,114,744.

Specification of Letters Patent.

Patented Oct. 27, 1914.

Application filed October 1, 1913. Serial No. 792,903.

To all whom it may concern:

Be it known that I, ROBERT FRIEND, a citizen of the United States, residing at Lowell, in the county of Middlesex and State of Massachusetts, have invented a new and useful Apparatus for Sealing Waxed Papers, of which the following is a specification, reference being had therein to the accompanying drawings.

10 This invention relates to an apparatus for sealing waxed or paraffin wrappers and is designed with special reference to the wrapping of bread and the like. The great desideratum in this kind of machine has been, 15 not only to provide a cooling means which will remain cool in spite of its close connection with the heating means, but a cooling means which will not have a tendency to loosen the end folds of the packages to be sealed. The constructions hitherto employed to accomplish these results have proven inefficient. Either the cooling means has not remained cool enough, after the machine has been in operation a short time, 20 to congeal the melted wax or paraffin sufficiently to allow it to withstand the strain of the end portions tending to resume their original position, or, if the cooling means do remain sufficiently cool for this purpose, 25 nevertheless said cooling means have been so constructed that the sealing has been improperly performed. When the package to be sealed leaves the heaters and is thrust forward into the cooling sections, the wax on the end folds is in a melted condition; the wax on the outside of the folds coming into contact with the cold surface of the cooling means immediately congeals, causing the outside of the folds to adhere to the cooling 30 means. Since the inner portions of the folds naturally do not cool so quickly as does the outside portion, which is in direct contact with the cooling means, it follows that the adhesion between the inside of the folds and 35 the end of the package is not so strong or firm as that between the outside of the folds and the cold surface of the cooling means; and it does not become so until the inner portions of the folds attain the temperature of the outer portion. This cannot take place until the lapse of a period of time longer than the package is allowed to remain in the position it occupies when first placed in the cooling means; consequently, when the 40 package is displaced, the force necessary to

break the joint formed between the outside of the folds and the surface of the cooling means tends also to break the joint formed between the inner portion of the folds and the end of the package. The result has been 60 that when such package leaves the machine the sealing has been so improperly performed that upon the slightest handling of the package the folds become loosened and resume their original position.

The present invention contemplates a construction wherein the heated portion is not only separate from the cooling end, but all friction between the folds and the cooling trough is eliminated, with the result 70 that the work of sealing the package is not only more expeditiously performed, but also results in a more perfect sealing. This is accomplished by constructing the cooling end of the machine in such manner that the 75 pressure exerting means come into contact with each package intermittently. The package is retained until it is sufficiently cooled and then discharged; whereupon that portion of the cooling means which retained 80 the package is allowed to cool until it is again brought into contact with another package.

The object of the invention, then, has been to produce an improved package sealing machine with provision for holding the folded ends of the package without relative motion between the folds of the package and the cooling means, and, also, to cause this cooling means to act intermittently. These 85 and other objects apparent to one skilled in the art, are embodied in the construction herewith presented and are hereinafter described and particularly defined in the claims.

Other objects of the invention will be more specifically pointed out and described hereinafter.

In the accompanying drawings illustrating the preferred form of my invention, 100 Figure 1 is a plan view of a machine for sealing waxed wrappers constructed and operated in accordance with my invention; Fig. 2 is a side elevation of the same looking upwardly in Fig. 1 and Fig. 3 is a side elevation of the table portion of the machine looking downwardly in Fig. 1.

Briefly, my apparatus comprises a suitable table or stand provided with means for applying heat to the waxed wrapper as it is 110

folded around the bread or other object in order to seal the joints and with means for applying pressure to the sealed joints of the wrapper until the latter cools.

5 In the illustrated embodiment of the invention my apparatus comprises a suitable table or bench which may be of any form or shape consistent with its purpose, having a top 5 supported by legs or standards 6 shown as united midway by horizontal rods 7 supporting a shelf 8. This table is provided with means for heating the bottom fold of the wrapper and also with heating and pressing means for the end folds. These two 10 means are preferably separate although they may be combined if desired.

The means employed for heating the edge of the paper which lies on the bottom of the loaf consists of a heating plate 10 preferably located in the center at one end of the table. This plate may be heated by any suitable means but as shown it is heated by electricity in the usual well known manner controlled by a switch 11. Arranged on one 20 side of the plate 10 is a sheet 12 of metal or other suitable material, having perforations 13, which sheet serves as a cooling means, to cool the wrapper after the bottom has been sealed on the heating plate 10.

30 For the purpose of heating, sealing and cooling the ends of the package, I provide the following means: Supported at some distance above the top of the table by standards 14 are two flat parallel strips 15 which serve as supports or guides for the bread or other package, while the ends are being folded, sealed and cooled. Arranged on each side of the guides 15 is a heating plate 16 and a cooling belt 17. The heating plates 40 may be heated by electricity, as shown, or in any other suitable manner. The interior construction of the heating plates is not shown in the drawings, as it is well known and constitutes no part of the invention. The 45 electric current passes through the wire 18 and is controlled by the switch 29. On one side the plates are each provided with a flaring guide 19 to finish the folding operation as the bread is advanced by hand to a position between the two plates. Each cooling 50 belt 17 arranged upon the opposite side of the heating plates, is preferably made of leather because it will not absorb heat from the heating plates and is perforated in order to 55 accelerate the cooling of the wrappers. Each belt is mounted on pulleys 20 rotatably mounted in a vertical plate 21 supported by standards 22. The heating plates are each supported by a standard 23 and in 60 order that the two sets of heating plates and cooling belts may be moved to and from each other in order to regulate the distance between and thereby accommodate loaves or packages of different dimensions, the standards 22 and 23 of each set are secured to a

movable slide 24 arranged in the top of the table. The movement of the two slides 24 is controlled by a right and left screw bar 25 operated by a handle 26, the screw bar being threaded through nuts 27 fastened to the underneath surface of each slide 24 and by turning the handle 26 the slides may be moved toward or away from each other in order to decrease or increase the distance between the two sets of heating plates and 75 cooling rolls.

To illustrate the operation of my apparatus, I have shown in the drawings, Figs. 1 and 3, a loaf of bread 30 in various positions as it is manipulated during the course 80 of a wrapping operation. Referring first to Fig. 3, the operator places a loaf 30 bottom side up upon a pile of wrappers 31 which are secured in position by a pin 32 set in an angle piece 33 on the edge of the 85 table. The free end of the wrapper is then folded around the loaf which is moved to the right separating the wrapper from the pin 32. In this movement the loaf is turned over which completes the wrapping and 90 brings the left hand edge of the sheet 31 on the bottom of the loaf. At the end of this movement the loaf is deposited upon the heating plate 10 bottom down and allowed to remain there until another loaf is 95 wrapped and displaces it. The first loaf is then pushed from the heating plate to the cooling sheet 11. During the short period of time that the first loaf remains upon the heating plate, the wrapper is heated and 100 the wax softened so that the weight of the loaf is sufficient to seal the bottom joint, and this sealing is completed by the cooling of the wrapper on the sheet 11. So far as this operation is concerned I have found that 105 the weight of the loaf operates to secure an effective sealing since this joint on the wrapper is not subjected to any substantial strain. From the cooling sheet 11 another operator transfers the loaf to the heating 110 plates 16 and in doing so, he grasps the loaf with one hand on each end, gathering in the sides of the wrapper on each end with the fingers and leaving the bottom of the wrapper extending outwardly. In this position the loaf is lifted and pushed between the guides in such a position that it rests on one side upon the supports 15 with the top of the loaf toward the operator, as shown in Fig. 1. As the loaf is pushed inwardly toward the heating plates 16, the guides 19 cause the ends of the wrapper to be folded up against the ends of the loaf and when it reaches the heating plates the wrapping operation is completed. The loaf is 120 allowed to remain between the heating plates until a second loaf is wrapped and is pushed into position between the plates thereby forcing the first loaf forward between the 125 belts 17. This operation is continuous and 130

- the first loaf is gradually forced along the guides 15 as each additional loaf is wrapped and pushed between the heating plates. The latter are of a temperature sufficient to melt 5 the wax or paraffin on the wrapper and the end folds are thereby sealed and by the time the loaf has reached the end of the belts (i. e. the right hand side in Fig. 1) the wrapper has cooled and the folds are 10 firmly bound together.
- It is to be observed that one of the most important features of my invention is that the means for sealing the ends of the package are adjustable thereby permitting the 15 apparatus to be instantly adapted for packages of different sizes. This feature also enables the operator to regulate the amount of pressure exerted upon the ends of the package by the heating plates and the pressure exerting means. It is also to be noted 20 that the pressure is continued until the wrapper is entirely cooled thereby insuring an absolute seal.
- I have found that by the use of my apparatus the wrapping process is greatly accelerated and the sealing of the packages absolutely insured. By employing leather belts I avoid all liability of heating the pressure exerting means, so that the wrapper on the 25 package begins to cool as soon as it is pushed between the belts. At the same time it will be noticed that the manual labor required in applying the wrappers is reduced to the minimum.
- 30 It is to be understood that my invention is not to be limited to the exact details of construction herein shown and described but may be embodied in other forms within the scope of the following claims.
- 35 40 What I claim is:—
1. An apparatus for sealing waxed or paraffin wrappers having a plurality of folds at the ends, comprising a wrapping table having means for heating the end 45 folds of the wrapper while the same are in a folded position and engaging means moving with the wrappers for exerting pressure upon said end folds to maintain them in a folded position until cooled.
  2. An apparatus for sealing waxed or paraffin wrappers having a plurality of folds at the ends, comprising plates for heating the end folds of the wrappers and means in which there is no relative motion 55 between the wrappers and said end pressure means for exerting pressure upon said end folds until they have cooled.
  3. An apparatus for sealing waxed or paraffin wrappers having a plurality of 60 folds at each end, comprising means for heating the end portions of the wrappers to be sealed and means coming in contact with said wrappers and moving therewith for exerting a continuous pressure upon said 65 end folds until they are cooled.
  4. An apparatus for sealing waxed or paraffin wrappers comprising means for heating the end folds of the wrappers under pressure and perforated cooling means moving with said wrappers and maintaining 70 a continuous pressure upon said end folds until the same have cooled.
  5. An apparatus for sealing waxed or paraffin wrappers comprising two heated plates for heating the end folds of the wrappers, and perforated engaging means moving with the wrappers for exerting pressure upon said end folds for maintaining them in a folded position until cooled. 75
  6. An apparatus for sealing waxed or paraffin wrappers comprising plates for supplying heat to the end folds of the packages to be sealed and perforated endless belts for maintaining pressure upon said folds by holding the packages between said belts until the same have cooled. 80
  7. An apparatus for sealing waxed or paraffin wrappers comprising heating plates for melting the wax or paraffin on the end folds of the wrappers, movable means for exerting pressure upon said folds until the wax or paraffin thereon has congealed, comprising endless belts passing around rotatable pulleys placed in juxtaposition to, and in alinement with, said heating 85 plates. 90
  8. An apparatus for sealing waxed or paraffin wrappers comprising a wrapping table having two heating plates and two perforated endless belts passing around pulleys placed in juxtaposition to, and in alinement with, said heating plates, said endless belts and said heating plates being laterally adjustable to accommodate packages of different sizes. 100
  9. An apparatus for sealing waxed or paraffin wrappers comprising two heated plates for heating the end folds of the wrappers, perforated engaging means moving with said wrappers for exerting continuous 110 pressure upon said end folds until the same have cooled and means for moving the plates and the engaging means to and from each other in order to accommodate packages of different sizes. 115
  10. An apparatus for sealing waxed or paraffin wrappers comprising two slides movable to and from each other to regulate the distance between, each of said slides being provided with means for heating the folds on one end of said wrapper and with means moving with said wrapper for maintaining a continuous pressure upon the folds on one end of said wrapper until the same have cooled. 120
  11. An apparatus for sealing waxed or paraffin wrappers comprising two slides movable to and from each other to regulate the distance between them, each of said slides being provided with a plate for heat- 125
  - 130

ing the folds on one end of said wrapper and with an endless belt moving with said wrapper for maintaining a continuous pressure upon the folds on one end of said wrapper until the same have cooled.

In testimony whereof, I hereunto set my hand in the presence of two subscribing

witnesses, this the twenty-ninth day of September, 1913.

ROBERT FRIEND.
